US00D531990S

(12) **United States Design Patent** (10) Patent No.: **US D531,990 S**
(45) Date of Patent: **** Nov. 14, 2006**

(54) **COMBINED AUDIO PLAYER AND HARD DISC DRIVE**

(75) Inventor: **Takayuki Kobayashi**, Tokyo (JP)

(73) Assignee: **Sony Corporation**, Tokyo (JP)

(**) Term: **14 Years**

(21) Appl. No.: **29/229,842**

(22) Filed: **May 13, 2005**

(30) **Foreign Application Priority Data**

Feb. 25, 2005 (JP) D2005-005429

(51) **LOC (8) Cl. 14-03**

(52) **U.S. Cl. D14/217; D14/167**

(58) **Field of Classification Search** ..... D14/160-168, D14/188, 217, 192-194, 496, 400, 401, 454, D14/455; D21/328, 329, 333; 455/344-351; 369/6-12, 75.11, 77.11, 77.21; 273/148 B; 463/1, 35-47

See application file for complete search history.

(57) **CLAIM**

The ornamental design for a combined audio player and hard disc drive, as shown and described.

DESCRIPTION

FIG. 1 is a perspective view of a combined audio player and hard disc drive showing my new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

Portions of FIGS. 1-6 that are shown as broken lines are for illustrative purpose only and form no part of the claimed design.

1 Claim, 6 Drawing Sheets

FIG. 1

FIG. 2

FIG. 3

FIG. 4

FIG. 5

FIG. 6
